ATTORNEY.

UNITED STATES PATENT OFFICE.

WESLEY M. DAVENPORT, OF ELGIN, ILLINOIS, ASSIGNOR TO ELGIN AUTO TOOL COMPANY, OF ELGIN, ILLINOIS, A CORPORATION OF ILLINOIS.

HOSE CLAMP.

Application filed March 27, 1922. Serial No. 547,187.

To all whom it may concern:

Be it known that I, WESLEY M. DAVENPORT, a citizen of the United States, residing at Elgin, in the county of Kane and State of Illinois, have invented a new and useful Improvement in Hose Clamps, of which the following is a specification.

My invention relates to an improved construction of hose clamp consisting of wires in substantially parallel relation passing around the hose to be clamped engaged at one end by a first head and at the other end by a second head and a clamping screw extending between the heads. The device is constructed in a manner requiring the wires in their clamping position to pass each head to reach the other head and thus movement of the screw between the heads in a direction to force the heads away from each other exerts a clamping tension on the wires and securely clamps the hose to the pipe end that it inserted in the end of the hose. By my construction I encircle the hose by the clamping wires somewhat more than the complete circumference of the hose and thus avoid the possibility of buckling or folding the hose at the location of the clamping heads in a direction tending to lift or move it from the surface of the pipe against which the hose is to be clamped, which is apt to occur with devices heretofore used in which the heads connected with the clamping band or bands are forced together to secure the clamping action and in which the clamping band or bands do not quite encircle the complete circumference of the hose. By my invention I also provide a convenient construction by which the clamping wires are securely held in a permanent manner by one of the heads and by which the engagement of the wires with the other head may readily be made by the user of the clamp, the wires being purposely left long enough to accommodate widely different sizes of hose so that the same device may be used to clamp either a small hose or a large hose and with whichever size of hose the clamp is used, it may be readily removed from the hose and readily used again with the same size of hose. By my invention I also provide convenient markings on the wires to facilitate clamping them to one of the heads with equal lengths of the wires between the heads depending upon the size of hose to be clamped, which insures placing substantially

the same clamping action upon each wire and the most effective operation of the heads during the clamping action.

The above and further objects of my invention will best be understood by reference to the accompanying drawings showing a preferred embodiment thereof in which—

Fig. 1 shows my improved clamping device in plan view in place upon a hose to be clamped,

Fig. 2 is an end view of the parts shown in Fig. 1, and

Fig. 3 is a plan view of the clamp before the wires are secured to one of the heads for use on a particular size of hose.

Similar numerals refer to similar parts throughout the several views.

As shown in Fig. 3 the clamp consists of a first head 10 through which the mid-portion of a wire 11 extends, said wire being bent at its mid-portion and passing through suitable receiving holes therefor in the head 10. The head 10 is preferably made by stamping and forming operations from sheet metal and consists of a central channel construction 10^a from one edge of which a flange 10^b is formed extending at substantially right angles with the adjacent wall of the channel and substantially parallel with the parts 11^a and 11^b of the wire, to form a surface for engaging the hose and prevent cutting of the same. The wall of the channel adjacent the flange 10^b has formed therethrough a clearance hole 10^c for receiving the end of the clamping screw 12 which passes through the channel portion 10^a so that its end rests against the inner face of the other wall of the channel immediately under the folded portion of the wire 11. In this manner a socket is formed for the end of the screw which retains the head 10 in place on the screw and the clamping action of the screw is exerted directly on that portion of the head engaging the wire so that the possibility of bending the head by the clamping action of the screw is avoided. The screw 12 passes through a nut 13 carried by a second head 14, which second head is preferably formed by punching and forming operation from sheet metal and consists of a channel portion 14^a containing the nut 13, from the outer edge of which a flange 14^b projects to reinforce the channel portion and form a convenient edge around which the parts 11^a and 11^b of the wire may be bent.

The flange 14^b has preferably formed in its outer edge notches 14^c to receive the bent portions of the wires and prevent displacement of them relatively to the head 14 when 5 the wire portions are bent to secure them to the head 14. It will be understood that while for convenience I form the wire portions 11^a and 11^b from a single piece of wire extending through the head 10 and folded 10 at 11, the portions 11^a and 11^b may be separate from each other if preferred and individually secured to the head 10.

The outer wall of the channel portion 14^a of the head 14 is provided with holes 14^d therethrough for the passage of the wire portions 11^a and 11^b and the opposite wall of said channel portion is cut away adjacent said wire portions so that its inner edge is just clear of said wire portions as they pass 20 through the head 14. To facilitate taking the wire portions of the same length between the heads 10 and 14 in securing the wire portions 11^a and 11^b to the head 14, I prefer to place markings 15 on the wires similarly 25 spaced from the head 10 so that when the clamp is in use, substantially equal tension may be exerted upon the wire portions and the heads may occupy a substantial parallel position in clamping the hose engaged by 30 the wires.

In placing the clamp upon the hose as shown in Figs. 1 and 2, the heads 10 and 14 are separated a sufficient amount so that when the wires are wrapped around the 35 hose the heads will occupy the position and relation indicated in Figs. 1 and 2 with the head 10 lying between the end portions of the wires to be secured to the head 14 and the head 14 extending over the wires adjacent to the head 10. The screw 12 is of 40 course in its outermost position in the head 14 at this time and the desired length of wires is determined and then by means of markings 15 the position of the edge of the flange 14^b on the wires may be determined. The device is then preferably removed from 45 the hose to secure the head 14 to the wires although if desired this may be done in place on the hose, and the wires are bent 50 around the edge of the flange 14^b in the notches 14^c and under the end portions of the channel portion 14^a of the head and then again bent adjacent the inner wall of the channel portion of the head over the wire 55 extending therefrom, thus securely fastening the end portions of the wires to the head 14. With the clamp in substantially the position indicated in Figs. 1 and 2, the screw 12 is turned to separate the heads 10 and 60 14 and by placing tension on the wires firmly compresses the hose against the pipe end contained within the hose. For convenience in Figs. 1 and 2 the pipe against which the hose is to be clamped is not shown since 65 the general nature of clamping devices of

this kind is understood and the hose itself is indicated at 16. It will be observed that the portions of the wires immediately adjacent the head 10 exert a clamping action on a hose under the head 14 adjacent the 70 flange 14^b and that the portions of the wires adjacent the head 14 exert a clamping action on the hose adjacent the flange 10^b of the head 10 and that the clamping action is uniformly exerted by the wires around the 75 entire circumference of the hose. Depending upon the degree of separation of the heads 10 and 14, this clamping action may be extended around the entire circumference of the hose or even a somewhat greater amount and thus any tendency of the hose to buckle at the heads is avoided. The position of the clamping heads shown in Figs. 1 and 2 is preferably that assumed on placing the clamp in position before beginning 80 the clamping action, and since each wire operates upon the hose independently of the other wire it will be observed that the entire circumference of the hose is clamped at two different places thus securing very 85 effective clamping action. It will further be observed that the screw 12 extends through the mid portion of the head 14 and engages the mid portion of the head 10, as 90 a result of which, if for any reason the wires are of slightly different length between the heads, the head 10 will operate as 95 an evener and cause substantially the same tension on each wire. Furthermore after 100 the clamp has been used with any particular hose it will be understood that if it is necessary to undo the clamped joint, by releasing the screw 12 the clamp may be removed from the hose and again used with the same size 105 hose just as effectively as in the first instance.

In carrying out my invention I find it advantageous to use wires having a circular cross section since they slip more readily on the surface of the hose in tightening the 110 clamp than they would if of flat cross section, but I do not limit myself in carrying out my invention to wires or bands of any particular cross section. It will also be observed that my improved clamp, while 115 particularly adapted for use with rubber hose, may also be employed in connection with any tubular structure as a clamping means where the material is sufficiently soft to yield to the clamping action described, as 120 for example soft copper pipe. In the following claims therefore in using the term wires as a part of the clamp construction I include within the meaning of the term, a wire or band of any form of cross section 125 that may be used in connection with my improved clamping device and in using the term hose in the claims I use it in the sense of any pipe or hose structure of a nature 130 permitting compression by means of my im-

proved clamping device. It will also be understood that I do not limit myself to the particular form of clamping screw described, as the entire function of said screw 5 is to separate the heads 10 and 14 in using the clamp and any arrangement or disposition of screw that will secure this result is included within the scope of my invention.

While I have shown my invention in the 10 particular embodiment above described it will be understood that I do not limit myself to this exact construction as I may employ equivalents known to the art at the time of the filing of this application without 15 departing from the scope of the appended claims.

What I claim is:

1. In a hose clamp, the combination of a first head, wires extending from said first head for encircling a hose to be clamped and passing said first head to engage a second head, a second head for engaging and retaining the ends of said wires, and a screw extending through one of said heads to engage 25 and exert a thrust upon the other of said heads, whereby tightening said screw separates said heads and exerts a clamping action by said wires on the hose, said second head having wire guideways and retaining 30 edges for receiving said wire ends and bending them into retaining joints to prevent said wires slipping in said second head.

2. In a hose clamp the combination of a first head, wires extending from said first head for encircling a hose to be clamped and passing said first head to engage a second head, a second head for engaging and retaining the ends of said wires, and a screw extending through one of said heads to engage 40 and exert a thrust upon the other of said heads, whereby tightening said screw separates said heads and exerts a clamping action by said wires on the hose, said wires having similar markings on them to facilitate securing equal lengths of said wires between said heads around the hose.

3. In a hose clamp, the combination of a first head, wires extending from said first head for encircling a hose to be clamped and 50 passing said first head to engage a second head, a second head for engaging and retaining the ends of said wires, and a screw extending through one of said heads to engage

and exert a thrust upon the other of said heads, whereby tightening said screw separates said heads and exerts a clamping 65 action by said wires on the hose, said second head having wire guideways and retaining edges for receiving said wire ends and bending them into retaining joints to prevent said wires slipping in said second head, and 70 said wires having similar markings on them to facilitate securing equal lengths of said wires between said heads around the hose.

4. In a hose clamp, the combination of two clamping members, wires extending 65 from one of said members and engaged in fixed relation thereby, the other of said members being conformed to engage and retain said wires at any desired distance from said one member, and a device for forcibly 70 moving said members relatively to each other to place a clamping tension on said wires, said other member having a projecting edge for engaging bends in said wires to hold them against the clamping action upon 75 them.

5. In a hose clamp, the combination of two clamping members, wires extending from one of said members and engaged in fixed relation thereby, the other of said 80 members being conformed to engage and retain said wires at any desired distance from said one member, and a device for forcibly moving said members relatively to each other to place a clamping tension on said 85 wires, said wires having markings on them equally spaced from said one member.

6. In a hose clamp, the combination of a first head, wires extending from said first head for encircling a hose to be clamped and 90 passing said first head to engage a second head, a second head for engaging and retaining the ends of said wires, and a screw extending through one of said heads to engage 95 and exert a thrust upon the other of said heads, whereby tightening said screw separates said heads and exerts a clamping action by said wires on the hose, one of said heads having a projecting edge for engaging sharp bends in said wires to hold them in desired 100 position on said head.

In witness whereof, I hereunto subscribe my name this 25th day of March, A. D. 1922.

WESLEY M. DAVENPORT.
